ATTORNEY

UNITED STATES PATENT OFFICE.

CHARLES JONAS, OF NEWTOWN, CONNECTICUT, ASSIGNOR TO FRANCIS A. DECKER, OF PHILADELPHIA, PENNSYLVANIA.

HOOK-FASTENING FOR GARMENTS.

SPECIFICATION forming part of Letters Patent No. 555,008, dated February 18, 1896.

Application filed March 14, 1895. Serial No. 541,677. (No model.)

To all whom it may concern:

Be it known that I, CHARLES JONAS, a citizen of the United States, residing at Newtown, in the county of Fairfield and State of Connecticut, have invented certain new and useful Improvements in Hook-Fastenings for Garments; and I do hereby declare the following to be a full, clear, and exact description of the invention, such as will enable others

10 skilled in the art to which it appertains to make and use the same.

My invention relates to certain new and useful improvements in hook-fastenings for garments, and has for its object to provide a 15 device of this description which may be readily secured in place and in which there shall be no projecting points to the fastening devices liable to injure the hand of the wearer, a further object being to prevent the accident 20 dental disengagement of the hook from the bar or eye to which it is attached and at the same time to permit the ready engagement of said hook and eye.

In the accompanying drawings, which form 25 a part of this application, Figure 1 is a perspective of my improved hook; Fig. 2, a plan view; Fig. 3, a bottom view; Fig. 4, a perspective of a preferred style of bar to be used in connection with said hook; Fig. 5, a sectional elevation showing the hook attached to a garment, but with the spur and pins not yet secured; and Fig. 6, a sectional elevation showing my improved hook as it appears when secured to a garment and used in connection 35 with an ordinary fastening bar or eye.

Similar numbers of reference denote like parts in the several figures of the drawings.

My improved hook is made entirely from sheet metal and is formed by stamping out 40 all the parts integral with each other in the manner which I will now explain.

1 is the body of the hook, and 2 a spur cut out so as to depend therefrom.

3 are side bars which extend forward from 45 the rear portion of the body and which are turned over at their junction at the forward extremity into the form of a hook 4, which latter it will be observed is cut away at its central portion so as to present a skeleton appearance.

5 is a tongue which extends forwardly from the rear of the hook-body and is formed with a bow 6, which rises upwardly within the hook 4, the forward extremity of this tongue being

brought down to substantially the plane of 55 the hook-body and terminating in a ledge 7, which latter is disposed rearwardly. This tongue is resilient, so that it will readily yield when the hook is engaged with any ordinary eye or bar and will return to its normal position after such engagement has been effected, so that said bar or eye cannot readily become disengaged by accident.

8 are pins which project forwardly from the rear of the hook-body on opposite sides of the 60 tongue 5 and normally rest upon the ledge 7, the latter affording a shield within which the points of the pins are housed, as will be readily seen from the drawings.

In attaching my improved hook to a garment the spur 2 and pins 8 are driven through the garment, as shown at Fig. 5, and the spur is then bent rearwardly up against the garment, while the pins are spread laterally and forced upwardly until they are finally pinched 75 or sprung into position upon the ledge 7, as shown at Fig. 6.

It will thus be seen that my improvement may be readily attached to a garment, while at the same time the pin-points are housed, 80 so that they cannot do any damage to the hand of the wearer.

I have shown a fastening-bar 9 provided with spurs 10 for securing the same within a garment; but I lay no claim to this bar in this 85 present application, and my improved hook may be used with any style of bar or eye.

Having thus described my invention, what I claim as new, and desire to secure by Letters Patent, is—

90 A hook for garments, comprising a body of sheet metal having at its rear end a depending spur and at its front end a skeleton hook, and provided with a resilient tongue extending forward from the rear end and formed 95 with a bow which rises upwardly within said hook and terminating in a rearwardly-disposed ledge, and also provided with pins which project from said rear end on opposite sides of said tongue and rest upon said ledge, substantially as shown and described.

100 In testimony whereof I affix my signature in presence of two witnesses.

CHARLES JONAS.
